SUCTION CLEANER

Application filed January 21, 1931. Serial No. 510,068.

The present invention relates to suction cleaners in general and particularly to a new and improved construction in which the height of the nozzle lips is automatically adjusted relative to the surface covering undergoing cleaning by variations in the nozzle vacuum. More specifically the invention comprises the provision, in a suction cleaner, of an improved automatic-height-adjusting construction in which the nozzle lips extend parallel to the plane of the surface covering in their various positions throughout the range of their movement.

It is an object of the present invention to provide a new and improved nozzle construction. It is another object to provide, in a suction cleaner, a new and improved automatic-height-adjusting means for the nozzle lips. A further object is the provision, in a suction cleaner, of an improved height-adjusting construction in which the nozzle lips are maintained parallel to the plane of the surface covering throughout their range of movement. A still further object is the provision, in a suction cleaner, of an automatic-nozzle-lip-positioning construction which will maintain the seal of the nozzle lips with the surface covering regardless of the variations of the height of that covering, and which will at all times maintain the nozzle lips parallel to the plane of the covering. Other and more specific objects will appear upon reading the following specification and claims and considering in connection therewith the attached drawings which form an integral part of this disclosure.

In the drawings, in which a preferred embodiment of the present invention is disclosed:

Fig. 1 is a partial side view of a suction cleaner, with the nozzle shown in section upon the line 1—1 of Figure 2, disclosing the present invention embodied therein;

Fig. 2 is a partial bottom view of the suction cleaner disclosed in Figure 1 embodying the present invention;

Fig. 3 is a section upon the line 3—3 of Fig. 2;

Fig. 4 is a view in perspective of a detail embodied in the present invention compris-

ing a frame to be pivoted within the nozzle;

Fig. 5 is a view in perspective of the sub-nozzle and the means for supporting it;

Fig. 6 is a view in perspective of a latch member;

Fig. 7 is a view of the spring which actuates the latch shown in Figure 6;

Fig. 8 is a schematic disclosure of the operation of the present invention.

In the operation of a suction cleaner upon a surface covering, and particularly that type of suction cleaner embodying positive agitating means such as a rotary agitator comprising rigid or positive beating elements, it is requisite for maximum cleaning efficiency that the surface covering be lifted from its supporting surface into contact with the lips of the suction cleaner nozzle in order that that portion of the covering between the lips may be contacted by the rotary agitator. The necessity for lifting the covering from the supporting surface is understood when it is explained that maximum cleaning effectiveness is only possible with the use of an agitator having rigid beating elements which function to vibrate and shake the covering between the nozzle lips, a function obviously impossible when that covering remains in contact with the supporting surface or floor as the blow of the striking element would only serve to smash the covering against the support. In the ordinary suction cleaner nozzle-height-adjusting means are usually provided in the form of means for raising or lowering the front or rear wheels of the suction cleaner. Such a manual adjustment

functions to raise the cleaner or rather pivot it about either the rear or the front supporting wheels, depending upon which are adjusted relative to the cleaner, the pivoting taking place about those wheels which remain stationary. Such an adjustment is valuable when the particular suction cleaner is to be used upon surface coverings of different types in which the height of the pile and the weight of the covering differ considerably.

That type of adjustment, however, fails entirely to compensate for irregularities in an individual surface covering, or in the supporting surface under that covering. Such

- irregularities often serve to tilt the machine thru allowing the supporting wheels to be raised or lowered relative to one another resulting in variations in the nozzle height, 5 and so the lips which are usually formed integrally with the nozzle, resulting in the breaking of the seal of the lips with the covering and allowing the air to rush into the nozzle without contacting the covering.
- 10 A further distinct disadvantage of the usual nozzle-height-adjusting means comprising the adjustment of the supporting wheels relative to the cleaner, lies in the fact that as the nozzle lips are raised or lowered relative to the surface covering, thru the machine being pivoted about the front or rear supporting wheels as an axis, the front lip is pivoted nearer to, or further from, the surface covering than the rear lip, it being positioned further from the pivot point. If the nozzle is in a low position the front lip contacts the surface covering at a lower height than the rear lip and so tends to prevent the raising of the covering into contact 20 with that lip. If the nozzle is in a relatively high position the reverse is true, the rear lip being the lower. This angular variation in the relative positions of the front and rear nozzle lips with the adjustment of the machine is extremely detrimental to the proper functioning of the cleaner thru providing improper nozzle lip contact with the covering.
- 25 In the suction cleaner constructed in accordance with the present invention no means are provided by which the suction cleaner nozzle as a whole is raised or lowered relative to the supporting surface for the purpose of varying the height of the nozzle lips.
- 30 Instead, the nozzle lips are made movable relative to the nozzle and suitably supported in a manner such that, regardless of their height relative to the surface covering, they are maintained parallel to the plane of that covering. The nozzle - height - positioning means constructed in accordance with the present invention are, further, automatically actuated by variations in the vacuum existing within the nozzle; variations in that 35 vacuum functioning to raise and lower the nozzle lips making manual adjusting means unnecessary.
- 35 Referring now to the drawings, the present invention is disclosed embodied in a modern suction cleaner which is partly shown in Figures 1 and 2. The suction cleaner comprises the usual parts found in the modern suction cleaner including a main casing or casting 1, which forms a nozzle 2, and a fan 40 chamber 3 which is interiorly connected with the nozzle 2. A motor casing 4 is positioned upon the main casing 1 immediately above the fan chamber 3 and houses a suitable driving motor for the suction-creating fan 45 provided in the fan chamber 3 for the pur-

pose of drawing air from the nozzle 2, thru the chamber 3, and exhausting it into a suitable dust bag, as in the usual suction cleaner. The cleaner is supported movably by front wheels, of which one is shown, being indicated by the reference character 5, and by means of rear supporting wheels, which are not shown, but which are positioned as in the usual suction cleaner of the present type. The front wheels are positioned within what is usually known as the nozzle, each being separated from the nozzle proper by means of an inwardly and rearwardly converging wall 6, which forms a wheel pocket at the rear outer corner of the nozzle. There are, of course, two such walls 6 and they also perform the useful function of providing the sides of the air passage leading from the mouth of the nozzle 2 to the fan chamber 3. A handle 7, pivoted to the fan chamber 3, is also provided and serves as means by which the cleaner may be propelled by the operator over the supporting surface.

Within the nozzle 2 and extending longitudinally therein is a rotary agitator 8 comprising helically extending beating elements 9, 9 and a brush element 10. The stationary shaft 11 of the agitator is held, at its ends, within suitable recessed seats 12, 12 formed in the end plates 13, 13 which are connected by the rigidly attached, spaced, surface-contacting, front and rear nozzle lips, 14 and 15. A pivoted latch 16 is provided upon each end plate 13 which is acted upon by a spring 17, also carried by each end plate 13, and functions, thru being provided with a cammed recess 18 which extends transversely across the seat 12 in the end plate 13, to lock the extended ends of the agitator shaft 11 in place within those seats.

The end plates 13, 13, supporting the agitator and, the nozzle lips 14 and 15, the construction forming a sub-nozzle, are mounted, relative to the cleaner, by horizontally extending parallel arms 19, 19 which are pivotally connected at their forward ends to the end plates 13 at spaced points in the same vertical plane. Arms 19, 19 are pivotally connected at their rearward ends within the wheel pockets, and so behind the nozzle proper, upon the rigid side members 20, 20 of the pivoted frame 21 which is itself pivotally carried by the supporting shafts 5a, 5a of the front wheels 5, 5. The frame 21 conforms closely to the side and front walls of the nozzle at their lower extremities where they define the nozzle mouth, the front cross member 22 of the frame extending closely adjacent the front wall of the nozzle and being secured thereto by means of the latch 23 which it carries and which is adapted to cooperate with a suitable pin 23a carried by the front wall of the nozzle.

With the construction in the operative relationship with the supporting frame 21 se-

- cured in position relative to the nozzle 2 by the latch means 23, the sub-nozzle, comprising the front and rear lips 14 and 15 and the end plates 13, 13, is carried by the frame 21
- 5 with the front nozzle lip 14 closely adjacent the cross member 22 of the frame 21, being separated therefrom only by a sealing strip 24, which may be of felt or similar material, and which is carried by the cross member 22
- 10 for the purpose of preventing the passage of air between the lip 14 and itself. The rear lip 15 of the sub-nozzle extends closely adjacent the forward edge of the bottom plate 25 of the air passageway leading from the nozzle to the fan chamber and is contacted by a sealing strip 26 of material similar to that comprising the sealing strip 24, for the purpose of preventing the passage of air between lip 15 and said bottom plate.
- 15 The initial, or "at rest" position of the sub-nozzle, and consequently the agitator which is carried thereby, is that shown in Figure 3. Gravity has pulled the sub-nozzle downwardly in the nozzle 2 as far as the stop pin 27, which extends between the side arms 19, 19 being carried by the side members 20, 20 on the frame 21, will permit. In this position the nozzle lips 14 and 15 extend a considerable distance below the lower extremity of the walls of the nozzle 2 and are adapted to contact the surface covering though it be lying flat on the supporting surface. Upon turning the starting switch for the cleaner and causing the motor 20 and the suction-creating fan to revolve a reduced pressure is created within the nozzle 2 which tends to collapse the housing formed by the nozzle casing on three sides, and the lips 14 and 15 and the surface covering
- 25 therebetween on the other side. This relationship is very similar to that found in a bellows and with the continued decrease in the pressure existing within the nozzle the external atmospheric pressure forces the surface covering, and the sub-nozzle which contacts it, upwardly and toward the main nozzle and from the supporting surface. The maximum upward displacement of the sub-nozzle is also limited by the stop pin 27, as is indicated in Figure 1, when that pin on each side of the nozzle contacts the lower arms 19, 19. With the surface covering lifted from the supporting surface the agitator, thru being carried by the sub-nozzle and positioned relative to the lips 14 and 15 at the most desirable position, functions with maximum efficiency to disturb and dislodge the embedded foreign particles from the surface covering and in particular that portion
- 30 of the surface covering between those lips. Upon the operation of the cleaner should the nozzle pass over a portion of the surface covering which is of decreased thickness or is irregular, or should the seal of the lips 14 and 15 with the covering be broken for
- any reason, the sub-nozzle will immediately drop and renew its contact with the covering, under the action of gravity, the vacuum within the nozzle being destroyed with the breaking of the seal. The presence of the seals 24 and 26 at the sides of the sub-nozzle serve to prevent the leakage of air there-around which would tend to decrease the effective vacuum within the nozzle and so the alertness of operation of the adjustment.
- 75 The mounting of the sub-nozzle by means of the parallel arms 19, 19 etc, upon the frame 21, which in operative relationship is rigidly secured within the nozzle 2, accomplishes the desirable result of maintaining the surface-contacting lips 14 and 15 in a horizontal plane, that is, regardless of the position of the sub-nozzle relative to the nozzle proper, the lips 14 and 15 are always parallel to the supporting surface of the cleaner. This function is best understood by reference to Figure 8 in which, in the left hand view, a schematic showing of the position of the parts of the sub-nozzle and its supporting means are shown at various heights relative to the nozzle. The lines A—B, A—B represent a pair of sub-nozzle supporting arms 19, 19 at one side of the nozzle, the points A, A being the pivot points about which the arms pivot, and the points B, B the pivotal connecting points between said arms and the sub-nozzle end plates 13, 13. The points B', B' and B'', B'' represent positions the pivotal connections of the arms 19, 19 at the end plates assume as the sub-nozzle is raised or lowered respectively, relative to the nozzle proper, equal distances from the central position indicated by the points B, B. From the showing it is clear that the lines B—B, B'—B' and B''—B'' are mutually parallel. In relation to the end plates of the sub-nozzle, and so the sub-nozzle itself, this means that any vertical adjustment is accomplished by translation 90 rather than by pivoting. Stated differently 95 this means that although the sub-nozzle is pivotally supported by the pairs of spaced arms 19, 19 that, in the movement of the sub-nozzle by the pivoting of the arms, the sub-nozzle is moved so that every plane therethru remains parallel to itself in all sub-nozzle positions. From this it follows that a plane thru the parallel lips of the sub-nozzle, which are also the lips of the nozzle, remains parallel to an initially parallel plane 100 105 110 115 120 125 130
- Referring now to the right hand schematic illustration in Figure 8 an ordinary construction is illustrated in which a single arm, represented by the line C—D, supports each end of the sub-nozzle. At the initial position the line E—E, representing a plane perpendicular to the nozzle lips, extends perpendicularly, but, it is noted, that upon pivoting the supporting arm, represented by

the lines C—D, to the angular positions indicated by the lines C—D' or C—D'' that the lines E—E' and E—E'' are not parallel to each other or to the line E—E. It is clear therefore, that if the plane of the nozzle lips is at all times perpendicular to the lines E—E in its various positions that upon the vertical adjustment of the lips relative to the nozzle that their angular positions will be varied and they will not remain parallel to the surface covering as in the present invention.

The present invention has been embodied in a simple construction which in no way complicates the repair of the cleaner or the removal of the agitator from the nozzle. To remove the agitator 8, or the sub-nozzle, from the nozzle 2 it is only necessary to permit the sub-nozzle to assume its lowermost position, that shown in Figure 3, at which time the frame 21 can be pivoted downwardly from the nozzle about its supporting pins 5a, 5a upon releasing the latch 23 from the front wall of the nozzle. With the frame 21 pivoted downwardly, as is clearly shown in dotted lines in Figure 1, it is possible to remove the agitator from the sub-nozzle by simply pivoting the latch 16 at each end against the force of a spring 17. The ends 30 of the agitator supporting shaft 11 can then be withdrawn from the openings 12, 12. To replace the agitator in the sub-nozzle the operation is the reverse from that just described.

35 I claim:

1. In a suction cleaner, a casing including a nozzle, a sub-nozzle including nozzle lips, means sealing said lips to said nozzle, and means supporting said sub-nozzle for vertical translation without tilting relative to said nozzle.

2. In a suction cleaner, a casing including a nozzle, a sub-nozzle including nozzle lips sealed to said nozzle, and means supporting said sub-nozzle for translatory movement including vertically spaced arms of equal length pivotally connected to said sub-nozzle and to said casing.

3. In a suction cleaner, a casing including a nozzle, a sub-nozzle including nozzle lips sealed to said nozzle, and means supporting said sub-nozzle for translatory movement including a plurality of spaced parallel equi-length arms pivoted at each end of said sub-nozzle to said casing.

4. In a suction cleaner, a casing including a nozzle, a sub-nozzle including nozzle lips, and means supporting said sub-nozzle for translatory movement including a plurality of spaced parallel equi-length arms pivoted to said nozzle and to said sub-nozzle at each of its ends.

5. In a suction cleaner, a casing including a nozzle, a sub-nozzle including nozzle lips sealed to said nozzle, and means supporting

said sub-nozzle for translatory movement including vertically spaced equi-length parallel arms at the ends of said sub-nozzle, said arms being pivoted to said nozzle and to said sub-nozzle.

6. In a suction cleaner, a casing including a nozzle, spaced surface-contacting lips movably supported relative to said nozzle, and means supporting said lips for translation including a pair of spaced members at each end of said lips, the members being pivotally connected relative to said lips in a vertical plane parallel to said lips and being pivotally connected to said casing.

7. In a suction cleaner, a casing including a nozzle, a sub-nozzle including nozzle lips within said nozzle, an agitator carried by said sub-nozzle adapted to contact the surface covering between said lips, and pivoted means supporting said sub-nozzle for translatory motion relative to said nozzle including vertically spaced equi-length arms at the ends of said sub-nozzle connected to it and to said nozzle.

8. In a suction cleaner comprising a nozzle, a pivoted frame normally secured within said nozzle and conforming to the shape thereof, a second frame comprising end plates and spaced cross-members extending therebetween movably supported on said first-mentioned frame, characterized by the fact that said cross-members function as surface-contacting lips.

9. In a suction cleaner comprising a nozzle, a pivoted frame normally secured within said nozzle and conforming to the shape thereof, a second frame comprising end plates and spaced cross-members extending therebetween movably supported on said first-mentioned frame, an agitator carried by said frame and extending between said cross-members, characterized by the fact that said cross-members function as surface-contacting lips.

Signed at Cleveland, in the county of Cuyahoga, and State of Ohio, this 24th day of December, A. D., 1930.

OLO C. WILLIS.
